AUTOMATIC STARTING SYSTEM AND
MEANS FOR HYDROCARBON ENGINESKenneth E. Lyman, Rockford, Ill., assignor to
Borg-Warner Corporation, Chicago, Ill., a cor-
poration of Illinois

Application December 5, 1932, Serial No. 645,726

9 Claims. (Cl. 290—38)

This invention relates to the automatic starting of hydrocarbon engines, particularly engines provided with a starting motor arrangement in which a lever is operable to first shift the motor gear into mesh with the engine gear and then to close the motor circuit controlling switch, the object being to provide electromagnetic means automatically controlled by the condition of the engine to control the actuation of the starting motor controlling lever.

An important object of the invention is to provide electromagnetic means for positively actuating the starting motor lever in both directions, that is, both for driving connection of the starting motor with the engine, and the disconnection from the engine, without depending upon springs for effecting the disconnection.

A further object is to provide switch mechanism conjointly controlled electromagnetically and mechanically to in turn control the electrical circuit for the lever actuating electromagnet, with the electromagnetic control of the switch mechanism depending upon the condition of operation of the engine and the mechanical control of the switch mechanism dependent upon the operation of the starting motor controlling lever by the electromagnet actuating means therefor.

A further object is to interpose a one-way connection or overrunning clutch between the motor shaft and the motor driving pinion whereby the pinion, after engagement with and starting of the engine, may be rotated by the engine gear independently of the motor shaft until the pinion has been positively unmeshed from the engine gear, in order to prevent injury to the starting motor.

The various features of my invention are incorporated in the structure and arrangement disclosed on the drawings, in which drawings:

40 Figure 1 is a side elevation of an engine showing my improved controlling apparatus mounted thereon;

Figure 2 is an enlarged side elevation of the starting motor with part of its frame and the engine frame in section and with the actuating magnet and electromagnetic switch mechanism more or less diagrammatically illustrated, and showing also the interconnecting electrical circuits;

50 Figure 3 is a view similar to Figure 2 but showing the positions of the parts while the engine is being started by the motor;

Figure 4 is a view similar to Figure 3 showing the positions and arrangement of the various parts immediately after the engine has been

started and with the motor about to be disconnected from the engine;

Figure 5 is an enlarged vertical diametral section of a circuit controlling vacuum responsive device; and

Figure 6 is an enlarged interview of the run over clutch interposed between the motor shaft and the motor driving pinion.

Referring to the drawings, Figure 1 more or less diagrammatically indicates a hydrocarbon engine E having the intake manifold 10 to which fuel is supplied by the carburetor 11, the starting motor M being associated with the engine and controlled by mechanism designated as a whole by C.

The starting motor shown has the armature shaft 12 projecting through the compartments 13 and 14 in the frame 15, the engine starting gear ring 16 extending into the compartment 14. Mounted on the shaft 12 within the compartment 13 is the hub sleeve 17 which at its inner end has bearing in the cross wall 18 between the compartments, the hub at its outer end carrying the disc 19 having the circumferential groove 20. A key 21 secures the hub to the shaft for rotation therewith but for permitting longitudinal shift of the hub on the shaft. Within the compartment 14 is a one-way connection or overrunning clutch comprising the cam member 22 secured to the inner end of the hub sleeve, and the cylindrical shell 23 surrounding the cam member and having the hub 24 journaled on the inner end of the sleeve 17, to which hub is secured the driving pinion 25. The cam member 22 has the cam notches 26 spaced around its periphery in each of which is a clutch member shown in the form of a ball 27. An annular plate 28 is secured to the outer end of the shell 23 and overlaps the cam member so that the cam member is confined within the shell. Referring to Figure 6, when the shaft 12 and the cam member 22 are rotated in clockwise direction the clutch balls will wedge between the cam member and shell and the shell will rotate with the shaft. Upon rotation of the shaft in the opposite direction the clutch balls will be released and the shell may rotate independently of the shaft and cam member in clockwise direction. When the sleeve 17 with the clutch structure thereon is shifted toward the gear ring 16 the pinion 25 will mesh with the gear ring for starting of the engine when the motor circuit is closed, and after starting of the engine the pinion and clutch shell may rotate independently of the sleeve and the motor shaft until the motor circuit is inter-

rupted and the pinion is withdrawn from the gear ring.

A spring 29 encircling the sleeve 17 between the disc 19 and the wall 18 resists inward shifting of the sleeve and normally holds it in outer position with the pinion 25 unmeshed from the gear ring 16 and with the clutch shell against the wall 18, as shown in Figure 2. Extending into the compartment 13 through an opening 10 30 is a lever 31 journaled intermediate its ends on a shaft 31' and forked at its inner end, the legs 33 and 33' having cylindrical pins 34 at their ends for engaging at diametrically opposite points in the groove 20 of the disc 19 so that 15 when the lever is rotated the disc and sleeve 17 may be shifted inwardly against the force of the spring 29 to effect meshing engagement of the pinion 25 with the gear ring 16, as shown in Figure 3.

20 Mounted on the frame of the motor M is a switch box 35 from which extends a switch plug 36 into the path of an abutment 37 extending from the lever 31 above its fulcrum. A spring 38 tends to hold the switch plug in outer or circuit opening position, and the spacing of the plug relative to the lug 37 is such that when the lever is rotated the sleeve 17 will be shifted for meshing the pinion 25 with the gear ring 16 whereafter the abutment lug will depress the 25 switch plug for closure of the motor circuit. When the plug is shifted in it will electrically connect contacts 39 and 40, the contact 39 having the terminal post 41 mounted on the outside of the switch box 35 and the contact 40 connecting with one terminal of the motor windings whose other terminals are grounded, the terminal post 41 being connected by a conductor 42 with the positive pole of the battery B whose other terminal is grounded.

40 For operating the lever 31 for positive connection or disconnection of the motor relative to the engine I provide an electromagnetic actuating structure designated as a whole A. This structure comprises a spool 43 of non-magnetic material on which winding sections or coils 44 and 44' are applied and in the bore of the spool an armature or core 45 is shiftable when the coils are energized. A stem 46 extends from the armature and at its outer end carries a clevis 47 which receives and is pivoted to the upper end of the lever 31 by a pin 48. When the lever 31 is in retracted position and the motor is disconnected the armature 45 is centered relative to the coil 43' and then, upon current flow through the winding 44, the armature will be attracted and shifted to center relative to the coil 44, such shift of the armature causing rotation of the lever 31 for driving connection of the motor with the engine and for closure thereafter of the motor circuit. When current flow through the coil 44 is then interrupted and circuit through the coil 44' is closed, the armature will be drawn back to center relative to the coil 44' and the lever 31 is positively retracted for opening of the motor circuit and disconnection of the motor from the engine. With such positive operation of the lever 31 the spring 29 may be comparatively light and its function may be solely to hold the sleeve 17 in its retracted position when the circuits through the electromagnet coils are open. In this function, the spring 29 may be assisted by another spring 49 which may also be comparatively light and may be connected with the upper end of the lever.

75 For controlling the circuit for the electromag-

net coils 44 and 44' I have provided a switch structure S. The switch structure shown comprises a head 50 having switch arms 51 and 52 extending in opposite directions therefrom, the head being pivoted on a pin 53. Contacts 54 and 55 are associated with the ends of the arms 51 and 52, the contact 54 being connected with one terminal of the coil 44 and the contact 55 being connected with one terminal of the coil 44', the other terminals of the coils being grounded. The head 50 has the arm 56 extending downwardly therefrom between springs 57 and 58, these springs tending to normally hold the head in position with the switch arms 51 and 52 disengaged from the contacts 54 and 55.

The operation of the switch S is automatically controlled conjointly by the operating conditions of the engine and the movement of the electromagnet A for actuation of the lever 31. The control of the switch by the operation condition of the engine is electromagnetically accomplished by an electromagnet structure T. This structure comprises a spool 59 of non-magnetic material carrying a coil 60, an armature or core 61 being shiftable in the bore of the spool. The stem 100 62 extending from the armature core carries a pin 63 engaging in the slot 64 in the upper end of the arm 65 extending upwardly from the switch head 50 so that when the stem 62 is shifted longitudinally the switch head will be rotated for engagement of its contact arms with the contacts 54 or 55. Normally when the switch S is open the armature core 61 is to the left of the electromagnetic center of the coil 60 and then when current is sent through the coil the armature 110 core will be shifted toward the right for rotation of the switch head for engagement of the switch arm 51 with the contact 54. The return movement of the armature core 61 is mechanically accomplished. The electromagnet structures 115 A and T and the switch S may be enclosed within a housing 66 through the side wall of which the stem 46 of the armature core of the electromagnet structure A may project for engagement with the lever 31. Above the lever a bracket 67 extends from the housing 66 and supports a pivot pin 68 for fulcruming a lever 69 intermediate its ends. At its lower end the lever has the pin 70 engaging in the forked upper end 71 of the lever 31 and at its upper end the lever 69 has a block 72 pivoted thereto which has the 120 guide channel 73 for receiving the outer end of the stem 62 of the armature core 61, this stem extending through the side of the housing 66. Secured at one end to the lever 69 and encircling 125 the stem 62 is a comparatively light spring 74 and on the stem 62 is the abutment 75 for the spring, this abutment being normally adjacent to the end of the spring but with the spring relaxed. With this arrangement, when the armature 61 is shifted electromagnetically outwardly the abutment 75 will engage with and compress the spring 74 and when the lever 31 is rotated by the electromagnetic structure A for meshing of the motor pinion with the engine, the lever 69 will be rotated and the spring 74 will be further compressed, as shown in Figure 3. Then when the current flow through the coil 60 is interrupted and the armature 61 is released the spring 74 130 will expand and shift the stem 62 and the armature 61 inwardly for rotation of the switch head 50 and engagement of the switch arm 52 with the contact 55, as shown in Figure 4. Current flow at this time through the coil 44' will cause 135 retraction of the lever 31 for disconnection of

the motor from the engine and the lever 69 will be rotated to its normal position for withdrawal of the spring 74 from the abutment 75 whereupon the switch head 50 will be returned to its neutral 5 circuit opening position by the springs 57 and 58.

The circuit for the electromagnet structure T is primarily controlled preferably by the ignition switch I. This switch is shown as comprising the switch blade 76 connected by conductor 76' 10 with the positive terminal of the battery B, and two switch buttons 77 and 78 are provided for the switch blade. The switch button or contact 77 is shown connected with one terminal of the primary winding of an ignition coil D, the other 15 terminal of the winding connecting with the circuit breaker arm 79 which engages the breaker cam 80 connected with the ground. The other switch contact 78 is connected by conductor 81 with one terminal of the winding 60 of the 20 electromagnet structure T, the other terminal of this winding being grounded. However, the energizing circuit for the structure T should be opened as soon as the engine has been started and is self-operating in order to release the 25 armature 61 for mechanical operation of the switch S and disconnection of the motor M from the engine by the electromagnet structure A. I have shown a structure G responsive to the 30 vacuum in the engine manifold 10 for automatically governing the energizing circuit for the structure T. The structure G is shown as comprising the housing walls 82 and 83 connected together by flanges which secure the periphery of a diaphragm 84. The diaphragm divides the 35 housing into two chambers 85 and 86, the chamber 86 being vented to atmosphere through the opening 87. The chamber 85 is connected by suitable duct 88 with the engine manifold 10.

The diaphragm carries a contact 89 opposed 40 to the contact 90 carried by the housing wall 82 but insulated therefrom. When the engine is at rest or is being turned by the starting motor the manifold suction will be too low to influence the diaphragm 84 and the contact 89 45 thereon will stay in engagement with the contact 90, but as soon as the engine has been started and is self-operating the suction will be materially greater and will then deflect the diaphragm 84 to disengage its contact 89 from the 50 contact 90. The contact 89 is grounded while the contact 90 is connected by conductor 91 with a terminal of the coil 60. The conductor 76' extending from the battery B is connected by conductor 92 with the head 50 of the switch S. 55 Briefly summarizing the operation of the system, when the ignition switch I is open and the engine is at rest, the switch S is in its neutral or circuit-opening position and is so held yieldably by the springs 57 and 58, as shown in 60 Figure 1.

For starting the engine the ignition switch I is moved into engagement with the terminals 77 and 78 for connection of the ignition system and for closure of the circuit for the electromagnet 65 T, this circuit being from the battery through conductor 76', the ignition switch, conductor 81, coil 60, conductor 91 and the engaging contacts 90 and 89 of the governor device G. The armature 61 will be shifted outwardly to the center of the coil 60 and the switch head 50 will be rotated 70 and the switch arm 51 engaged with the contact 54 whereupon current flows from the battery through the conductors 76' and 92, switch arm 51 and contact 54 and through the coil 44 to ground 75 and the armature 45 of electromagnet structure

A will be shifted outwardly and the lever 31 will be rotated to cause inward shift of the sleeve 17 and meshing engagement of the motor pinion 25 with the engine gear ring 16. As soon as this meshing engagement has been established the 80 lug 37 on the lever 31 depresses the switch plug 36 for closure of the motor circuit extending from the battery through the contacts 39 and 40 and through the motor windings to ground and the engine is now being turned by the motor for 85 starting thereof.

Upon outward shift of the armature 61 of the electromagnet T the abutment 75 initially compressed the spring 74 and then when the lever 69 was rotated by the outward swing of the lever 90 31 the spring 74 was finally compressed, the relative positions of the parts during starting of the engine by the motor being illustrated by Figure 3.

As soon as the engine has been started and is self-operating the vacuum in the manifold will become sufficient to withdraw the diaphragm 84 for separation of its contact 89 from the contact 90 and opening of the energizing circuit for the electromagnet T. While this circuit is closed the magnetic effort on the armature 61 is sufficient 95 to resist inward shift of the stem 62 on armature by the compressed spring 74, but as soon as the circuit is opened then the spring becomes effective and the stem and armature are shifted inwardly beyond their normal position for rotation of the switch head 50 and connection of the switch arm 52 with the contact 55 after disengagement of the switch arm 51 from the contact 54 and the parts are then arranged as shown in 100 Figure 4. The circuit through the coil 44 will 105 now be broken but the circuit through the coil 44' will be closed and the armature 45 will be drawn inwardly for positive rotation of the lever 31 back to normal position with the motor pinion 25 unmeshed from the engine gear ring 16, 110 the motor circuit having been opened by release of the lever abutment 37 from the switch plug 36. Such retraction of the lever 31 will rotate the 115 lever 69 back to normal position in which the spring 74 is withdrawn from the abutment 75 120 on the stem 62 and then the spring 57 acting against the arm 56 will swing the switch S back to normal, circuit opening, position as shown in Fig. 2.

The armature 45 when shifted inwardly exerts 125 a powerful pull on the lever 31 assisted by the springs 29 and 49, the motor being thus rapidly unmeshed from the engine, and the springs then hold the motor pinion in its unmeshed position. As before stated, the springs may be comparatively light and of just sufficient strength to hold the motor pinion in unmeshed position in order 130 that the spring resistance will not offer too much resistance to the outward shift of the armature 49 for swing of the lever for movement of the 135 motor pinion into meshing engagement with the engine gear ring.

So long as the engine is self-operating with the 140 vacuum of sufficient strength to keep the governor switch G open, the starting motor will remain disconnected, but should the engine stall or accidentally stop the governor switch will reclose the circuit for the electromagnet T and the engine connection cycle will be repeated for automatic restarting of the engine.

Upon stalling or accidental stopping of the engine, the circuit for the electromagnet T will be closed, but the time required for functioning of the electromagnets and the levers will be sufficient 145 to permit the engine to come substantially 150

or fully to a complete stop before the motor pinion is meshed with the engine gear ring and the motor switch is closed. Should the engine still be turning when the governor switch is reclosed and the motor pinion is moved into mesh with the engine gear ring, the pinion and the overrun clutch shall rotate independently of the motor shaft until the motor switch is closed.

While I have shown and described a pressure control unit G as illustrative of a control unit whose actuation depends upon the operation or non-operation of the engine, it will be understood that the present invention is equally useful with any standard type of control unit such as for example as a mechanical governor or a unit connected in an electrical circuit of the engine which shifts from one position to another because of operation or non-operation of the engine.

I do not desire to be limited to the exact construction and arrangement, and operation shown and described as changes and modifications may be made without departing from the scope and spirit of the invention as defined by the appended claims.

25 I claim as my invention:

1. The combination with a hydrocarbon engine and a starting motor therefor, of a driving train between said motor and engine, and an electromagnet structure furnishing the power for positively closing said driving train for starting of the engine by the motor and for positively opening said train for disconnecting the motor.

2. In combination, a hydrocarbon engine, a starting motor therefor, coupling means for coupling said motor to the engine for starting of the engine by the motor, an actuator for said coupling means, an electromagnetic device for operating said actuator comprising two winding sections and an armature responsive to the magnetic fields set up by said windings and connected with said actuator, current supply circuits for said windings, and a switch operable to selectively close said circuits through said windings for positive movement of said actuator by said armature for coupling or uncoupling movement of said coupling.

3. In combination, a hydrocarbon engine, a starting motor therefor, coupling means for coupling said motor to the engine for starting of the engine by the motor, an actuator for said coupling means, an electromagnetic device for operating said actuator comprising two winding sections and an armature responsive to the magnetic fields set up by said windings and connected with said actuator, current supply circuits for said windings, a switch operable to selectively close said circuits through said windings for positive movement of said actuator by said armature for coupling or uncoupling movement of said coupling, an electromagnet comprising an energizing winding and an armature member connected with said switch, closure of said energizing winding causing movement of said armature and of said switch for operation of said actuator by said electromagnet device for movement of said coupling means to coupling position, and means effective upon opening of said electromagnet energizing circuit for moving said switch for operation of said actuator by said electromagnet device to move said coupling means to uncoupling position.

4. In combination, a hydrocarbon engine, a starting motor therefor, coupling means for coupling said motor to the engine for starting of the engine by the motor, an actuator for said coupling means, an electromagnetic device for operating

said actuator comprising two winding sections and an armature responsive to the magnetic fields set up by said windings and connected with said actuator, current supply circuits for said windings, a switch operable to selectively close said circuits through said windings for positive movement of said actuator by said armature for coupling or uncoupling movement of said coupling, an electromagnet having an energizing circuit and adapted upon closure of said circuit to move said switch for operation of said actuator by said electromagnet device to move said coupling means to coupling position, and mechanical means controlled by the coupling movement of said actuator to move said switch for operation of said actuator by said electromagnetic device to uncouple said motor from the engine upon opening of said electromagnet energizing circuit.

5. In combination, a hydrocarbon engine, a starting motor therefor, movable coupling means for coupling said motor with said engine for starting thereof, an electromagnetic actuator comprising two energizing coils and an armature, a connection for transmitting the movement of said armature to said coupling means, energizing circuits for said coils, a switch movable to selectively close said energizing circuits for movement of the armature in one direction to cause movement of said coupling means for connection of said motor with said engine or for movement in the opposite direction for movement of said coupling means for disconnection of the motor from the engine, an electromagnet having an armature connected with said switch and a coil, an energizing circuit for said electromagnet coil, a manually operable switch for primarily closing said energizing circuit for said electromagnet for operation of said switch by the electromagnet armature for response of the actuator to cause coupling of the motor to the engine for starting thereof, an automatic switch for said electromagnet energizing circuit adapted to automatically open said circuit as soon as the engine has been started, whereby said electromagnet armature will be released, and means for then actuating said switch for operation of said electromagnetic actuator to cause disconnection of the motor from the engine.

6. In combination, a hydrocarbon engine, a starting motor therefor, coupling means for coupling said motor to the engine for starting of the engine by the motor, an actuator for said coupling means, an electromagnetic device for operating said actuator comprising two winding sections and an armature responsive to the magnetic field set up by said windings and connected with the actuator, current supply circuits for said windings, a switch operable to selectively close said circuits thru said windings for positive movement of said actuator by said armature for coupling or uncoupling movement of said coupling means, an electromagnet comprising a winding and an armature connected with said switch for controlling the movement of said switch for operation of said electromagnetic device to cause coupling of the motor to the engine, an energizing circuit for said electromagnet winding, a mechanical means including a spring for controlling the movement of said switch in the opposite direction for actuation of said electromagnetic device to cause uncoupling of the motor from the engine, an ignition circuit for the engine, a switch for closing the ignition circuit and also the energizing circuit for said electromagnet windings and operation of said switch by the electromagnet armature resulting

- in coupling of the motor to the engine, means controlled by the electromagnetic device for causing said spring to exert energy on said switch tending to move said switch for operation of said electromagnetic device for uncoupling of the motor from the engine, the energized electromagnet preventing such operation by the spring, a governor switch for the electromagnet energizing circuit, and means controlled as soon as the engine has been started for causing opening of said circuit by said governor switch whereby the electromagnet armature will be released and said spring may become effective to cause movement of said electromagnetic device controlling switch for operation of said electromagnetic device to cause disconnection of the motor from said engine.
7. The combination with a hydrocarbon engine, of a starting motor therefor, electromagnetic means operable to positively connect said motor with the engine for starting thereof and to positively disconnect the motor from the engine, electrical circuits for said electromagnetic means, and means conjointly controlled by the engine and by the operation of said electromagnetic means for controlling said circuits.
8. The combination with a hydrocarbon engine and a starting motor therefor, of a driving train between said motor and engine, an electromagnet structure furnishing the power for positively closing said driving train for starting of the engine by the motor and for positively opening said train for disconnecting the motor,
- controlling circuits for said electromagnet structure, a switch for controlling said circuits, actuating means for said switch effective during closure of said driving train and tending to operate said switch for operation of the electromagnet structure to open said driving train, means controlled by the operating condition of the engine to resist such movement of the actuating means while the engine is being started by the motor but for releasing said actuating means for operation when the engine becomes self-operating.
9. The combination with a hydrocarbon engine of a starting motor therefor, electromagnetic means operable to positively connect said motor with the engine for starting thereof and to positively disconnect the motor from the engine, electrical circuits for said electromagnetic means and a controlling switch for said circuits, an electromagnet connected with said switch and adapted upon energization to set said switch for operation of said electromagnetic means to connect the motor with the engine, an energizing circuit for said electromagnet and a switch for said circuit, and actuating means effective during connection of the motor with the engine and tending to set said controlling switch for operation of the electromagnetic means to cause disconnection of the motor from the engine but being restrained by the electromagnet, opening of the electromagnet energizing circuit releasing said actuating means for setting of the controlling switch thereby.
